UNITED STATES PATENT OFFICE

92,616

DESIGN FOR A TOOTHBRUSH

Max Largever, Bronx, N. Y.

Application April 6, 1934, Serial No. 51,332

Term of patent 7 years

To all whom it may concern:

Be it known that I, MAX LARGEVER, a citizen of the United States, resident of Bronx, in the county of Bronx, and State of New York, have invented a new, original, and ornamental Design for Tooth Brushes, of which the following is a specification, reference being had to the accompanying drawing, forming part thereof.

Figure 1 is a front view and Figure 2 a side view of the tooth brush constituting my new design.

The dominant feature of the design consists of

an arrangement of an ornament in the form of a letter of the alphabet on the end of the brush handle, the letter A being used in the instant case, but it is understood that other letters of the alphabet may be substituted therefor without departing from the invention.

I claim:

The ornamental design of a tooth brush, substantially as shown and described.

MAX LARGEVER.
